UNITED STATES PATENT OFFICE

2,442,450

DOOR CLOSER

Carl S. Aspenwall, Chicago, Ill., assignor to The Eagle Lock Company, Terryville, Conn., a corporation of Connecticut

Application August 20, 1945, Serial No. 611,500

7 Claims. (Cl. 16—56)

1

This invention relates to an improved door closer, and has for one of its principal objects the provision of a device whereby doors can be closed automatically and without slamming and wherein this closing can be accomplished more efficiently than heretofore.

One of the important objects of this invention is to provide a door closing device which is of the hydraulic style and which will comprise a pair of pistons as distinguished from the usual single piston apparatus.

Another important object of the invention is to provide a door closer having a pair of pistons operating on a common crank shaft, which crank shaft is offset so that any possibility of a dead center is eliminated.

Another and further important object of the invention is to provide in a door closer of the hydraulic type a single valve whereby the flow of liquid from two cylinders may be controlled and regulated simultaneously.

Another object is the provision, in a door closer, of means for decelerating the speed of the closing door from the inception of its closing motion.

Other and further important objects of the invention will be apparent from the disclosures in the accompanying drawings and following specification.

The invention, in a preferred form, is shown in the drawings and hereinafter more fully described.

In the drawings:

Figure 1 is a perspective view of the improved door closer of this invention, showing a preferred form.

Figure 2 is a sectional view of the device taken on the line 2—2 of Figure 3.

Figure 3 is a vertical sectional view of the apparatus taken on the line 3—3 of Figure 4, looking in the direction indicated by the arrows.

Figure 4 is an end view of the door closer, certain interior parts being shown in dotted lines.

Figure 5 is a sectional view taken on the line 5—5 of Figure 4, looking in the direction indicated.

Figure 6 is a section on the broken line 6—6 of Figure 5.

Figure 7 is a section on the line 7—7 of Figure 5.

As shown in the drawings:

The reference numeral 10 indicates the main body portion of the improved door closer of this invention, the same being flanked by two cylinders 12 and 14, preferably integral with the main body portion 10. It will be noted from Figures

2

1 and 3 that the cylinders are offset and do not have a common longitudinal axis. This is mainly for the purpose of employing two pistons in the respective cylinders, which pistons operate on a single crankshaft.

One of these pistons, namely, that for the cylinder 12, is indicated at 16 and the piston for the cylinder 14 is indicated at 18.

Each piston is joined by means of respective connecting rods 20 and 22 to a single crank 24. As best shown in Figure 2, the crank 24 has a throw on one side of 205 degrees and on the other side of 155 degrees, so that there will be no dead center so long as the pistons are in motion. This offset of the crankshaft can be varied considerably within effective working limits from the 205°—155° ratio whenever such variation is desirable.

The crank 24 is mounted in suitable bearings 20 in the body portion 10, and its upper end projects beyond the top face of said body portion, this upper end terminating in a square shaft to which is attached one end of an adjustable arm 26 and to the other end of this arm 26 is attached 25 the outer end of another adjustable arm 28, the inner end of which is adapted to be affixed to the door frame or the like 30. The adjustable main arm 26 enables lengthening or shortening of the same in order to increase or decrease spring 30 power by means of a change of leverage, and also to govern the shaft revolution to accomplish a hold-open feature for the door by passing a dead center on the crank.

As will be noted from the drawings, each piston 16 and 18 surmounts a helical spring, these springs being shown at 32 and 34 respectively, and being positioned inside the cylinders 12 and 14 respectively. The inner ends of the springs are positioned against inwardly projecting annular ledges 40 of the respective cylinders, so that the springs will have a tendency to force the pistons outwardly at all times.

Each piston is provided with a ball valve as shown at 42, and the cylinders themselves, together with the body portion, are filled with a hydraulic liquid.

A tapered slot 42 is cut into the side of each cylinder, as best shown in Figure 2, and it will be noted that the larger end of each of these tapered slots is toward the rear of the cylinder.

A passageway 44 leads from the end of each cylinder and this joins a duct 46 in the body 10, which duct extends parallel to the cylinders and are joined by an offset duct 48 in the body 10, 55 and this passageway is controlled by a needle valve

3

50, which constitutes the only adjustment for the flow of hydraulic liquid through the apparatus. The needle valve 50 is mounted in a packing gland 52.

In operation, the device is full of a suitable hydraulic liquid and upon the opening of the door 54, the action of the arms 26 and 28, together with the crank 24, retracts the pistons 16 and 18 compressing the springs 32 and 34.

At the same time liquid goes past the ball valve 40 in the pistons 16 and 18.

Upon release of the opening force against the door, the springs 32 and 34 tend to force the pistons outwardly in the cylinders, accordingly imparting a closing movement to the door. The initial controlled closing motion of the door is relatively fast, owing to the fact that the larger portions of the tapered slots 42 are toward the rear of the cylinders and considerable hydraulic fluid is allowed to pass around the pistons during this first part of their motion outwardly.

As the pistons near the outward end of their travel, the taper of the slot restricts more and more the passage of liquid around the pistons and accordingly liquid must then be pushed through the passages 44 and 46 past the needle valve 50. Obviously, control of the passages by means of the needle valve will very accurately govern the speed of the closing movement of the door and allow the same to close in a fashion most to be desired.

The offsetting of the cylinders allows the use of a double throw crank, and the fact that the crank itself is in a 155 degree to 205 degree ratio eliminates a mechanical dead center, inasmuch as one piston is opposed to the other so that when one is on dead center, the opposite piston is in motion when the crank shaft is in the act of revolving about its center. This also provides for constant pressure so far as the hydraulic action is concerned.

The primary control of the pistons is through the tapered slot, and the small end of the slot comprises the end of the first control. This still leaves sufficient liquid for port and valve control.

The use of a single needle valve or adjusting screw which adjusts the flow of liquid from the ends of both cylinders and through a common orifice leading the liquid to a point behind the pistons comprises an important feature of the invention. Obviously, the liquid in the body 10, when the pistons are moving outwardly, is not under compression.

The ratio of the crankshaft offset can be varied within working limits to quite a departure from the 155°-205° relationship, so long as a dead center construction is avoided.

It will be seen that herein is provided a new and improved door closer which, while being composed of a minimum of parts, is considerably more efficient than those heretofore in use and which even comprise a greater number of moving parts. The offset crank whereby a mechanical dead center is eliminated, is an important new feature and the single regulating valve to control the motion of two pistons simultaneously will, it is believed, constitute a considerable advance in this art.

I am aware that many changes may be made and numerous details of construction varied throughout a wide range without departing from the principles of this invention, and I, therefore, do not propose limiting the patent granted hereon otherwise than as necessitated by the prior art.

I claim as my invention:

4

1. A door closer comprising a body, a pair of cylinders on the body, a piston in each cylinder, a spring behind each piston, tending to force the same normally outwardly, a supply of hydraulic fluid in the body and cylinders, a single regulating valve for fluid control, a crankshaft in the body and connecting rods between the crankshaft and the pistons, the crank being offset at approximately 205 degrees to 155 degrees relative to its circumferential path of travel.

2. A door closer comprising a body, a pair of non-aligned cylinders on the body, a piston in each cylinder, a spring behind each piston, tending to force the same normally outwardly, a supply of hydraulic fluid in the body and cylinders, a single regulating valve in the body for fluid control, a crankshaft in the body, connecting rods between the crankshaft and the pistons, the crank being offset, a telescopic arm mounted on the outer end of the crankshaft, and a further arm connecting the outer end of the telescopic arm to a door frame, the door closer body being mounted on a door.

3. In a door closer, a body, a crankshaft mounted in the body, a pair of opposed cylinders positioned on the body in non-aligned relationship, a piston movable in each cylinder, a connecting rod between each piston and the respective portion of the crankshaft, a ball valve in each piston, a spring behind each piston, a duct leading from the outer end of each cylinder back to the body portion, hydraulic fluid in the body, cylinders and ducts, and a single regulating valve for control of the liquid flow.

4. A door closer including a body, a pair of opposed cylinders on the body, a piston in each cylinder, a crankshaft for the pistons in the body, a spring behind each piston tending to force the same normally outwardly, ducts connecting the outer ends of the cylinders with the body, a supply of hydraulic fluid in the body, ducts and cylinders, a single regulating valve in one of the ducts, and a tapered slot in each cylinder wall, the small end of each slot being adjacent the outer end of each cylinder.

5. A door closer including a body, a pair of opposed non-aligned cylinders on the body, a piston in each cylinder, a crankshaft for the pistons in the body, a spring behind each piston tending to force the same normally outwardly, a supply of hydraulic fluid in the body and cylinders, ducts connecting the outer ends of the cylinders with the body, a single regulating valve in one of the ducts, and a tapered slot in each cylinder wall, the small end of each slot being adjacent the outer end of each cylinder for decelerated outward piston movement.

6. A door closer including a body, a pair of cylinders on the body, a piston in each cylinder, a crankshaft for the pistons in the body, a spring behind each piston tending to force the same normally outwardly, ducts connecting the outer ends of the cylinders with the body, a supply of hydraulic fluid in the body ducts and cylinders, a single regulating valve in one of the ducts, a tapered slot in each cylinder wall, the small end of each slot being adjacent the outer end of each cylinder for decelerated outward piston movement, and a pair of linked arms on the outer end of the crankshaft.

7. A door closer including a body, a pair of opposed cylinders on the body, a piston in each cylinder, a crankshaft for the pistons in the body, a spring behind each piston tending to force the same normally outwardly, a supply of

hydraulic fluid in the body and cylinders, ducts connecting the outer ends of the cylinders with the body, a single regulating valve in one of the ducts, and a tapered slot in each cylinder wall, the small end of each slot being adjacent the outer end of each cylinder for decelerated piston movement, the cylinders being non-aligned with respect to each other, and the crankshaft having approximately a 205-degree-155-degree offset.
